MACHINE FOR GRINDING CRANKSHAFTS

Herbert S. Indge, Westboro, Mass., assignor to
Norton Company, Worcester, Mass., a corpora-
tion of Massachusetts

Application November 26, 1938, Serial No. 242,444

12 Claims. (Cl. 51—120)

This invention relates to a machine for grinding crankshafts, and more particularly to a machine which will serve to grind or polish several crankshaft pins simultaneously.

5 The crankshafts as used in automotive engines have four or more crank pins which are offset relative to the central bearing axis of the crankshaft. These pins must be ground to extremely accurate dimensions and polished surfaces because of the rigid requirements of the automotive industry. Owing to the number and arrangement of the pins on the shaft, it is a slow and expensive operation to grind each one of these pins to the required surface, and it is, therefore, desirable to provide a mechanism which will grind all of the pins at the same time, as well as to shape each crank pin by means of a positively rotated grinding wheel which will true the pin throughout its entire 20 length.

It is, therefore, a primary object of this invention to provide a machine which will grind a plurality and preferably all of the crank pins of a shaft simultaneously.

25 A further object is to provide a machine of this type in which the pins are ground by wheels so arranged that they will grind throughout the full length of pins of different lengths.

A further object is to provide a machine in 30 which each pin is ground independently of the others by a grinding wheel so mounted and arranged that it may be adjusted towards and from the work independently of the other wheels.

Another object is to provide a crank pin grinding machine in which each pin is ground by a 35 rotating grinding wheel which is held always in correct relation with its associated pin as the latter is revolved.

A still further object is to provide a crank- 40 shaft grinding machine in which the grinding wheels for the different pins are separately mounted and yet are moved in unison and in timed relationship with the revolving crankshaft in such a manner that the flat side of each wheel 45 maintains abrading contact with its pin as the wheel and the pin revolve. Further objects will be apparent in the following disclosure.

Referring to the drawings, which illustrate one embodiment of the invention:

50 Fig. 1 is a partial front elevation of the machine with a crankshaft mounted in place for the polishing operation;

Fig. 2 is a vertical section on the line 2—2 of Fig. 1, parts being shown in full outline and other 55 parts broken away;

Fig. 3 is a fragmentary vertical section taken on the line 3—3 of Fig. 1 showing the head stock driving mechanism;

Fig. 4 is a section on the line 4—4 of Fig. 3, showing the crankshaft supporting and driving shaft;

Fig. 5 is a front elevation of the tailstock partly in section;

Fig. 6 is a fragmentary plan view of the machine with parts removed for clarity;

Fig. 7 is a sectional view of the grinding wheel spindle supporting and driving mechanism;

Fig. 8 is a fragmentary sectional view on the line 8—8 of Fig. 2 showing one of the master crankshafts;

Fig. 9 is an end view of the abrasive wheel and its support looking in the direction of the arrow 9 in Fig. 7 showing the abrasive wheel concentric with the axis of its driving member;

Fig. 10 is a similar view showing the grinding wheel adjusted to an eccentric position;

Fig. 11 is an end view on the line 11—11 of Fig. 7, with the cover removed;

Fig. 12 is a similar view on the line 12—12 of Fig. 7;

Fig. 13 is a view similar to Fig. 12 showing the grinding shaft in an eccentric position; and

Fig. 14 is a fragmentary sectional view on the line 14—14 of Fig. 2 showing the path of movement of the grinding wheel relative to the work.

In accordance with this invention, I have provided a machine for grinding or polishing a crankshaft, which comprises a grinding wheel mounted to grind a pin while the latter rotates and revolves relative to the axis of the shaft. It preferably has a set of independently movable 35

mounts arranged to hold the flat ends of abrasive wheels in contact with associated pins on the shaft as the latter revolve. Each wheel may be mounted eccentrically on a supporting spindle, and the wheel may be smaller in diameter than the length of the crank pin, the parts being so arranged that the abrasive of the wheel may travel in a planetary path and so grind 45 the length of the pin as it rotates and revolves. This eccentricity of the wheel axis may be adjusted, if desired, so as to permit grinding crank pins of different lengths. The abrasive wheels are each preferably driven by means of an independent motor directly connected to its spindle.

The mounts for the grinding wheel spindles are so supported and moved by synchronized master crankshafts that each wheel is caused to follow its associated pin on the revolving crank- 50

- shaft and maintain abrading contact therewith. The wheel mounts may also be so arranged that they may be moved away from the work, as by means of fluid pressure mechanism, to permit replacement of the crankshaft being ground. Each wheel may also be independently adjusted toward and from the work, and the parts are preferably so arranged that each wheel will be held under resilient pressure against the work.
- 10 All of these various features are shown combined in the mechanism illustrated in the drawings. As there shown, the base 10 of the machine carries a head stock 11 and tailstock 12 on which the crankshaft work piece 14 is suitably mounted. Each pin 15 of the crankshaft is adapted to be ground or polished by means of a separate wheel 16, which in the present embodiment, is shown as a cup shaped wheel removably mounted on the end of a wheel spindle 18.
- 15 As shown particularly in Fig. 7, the wheel spindle 18 is mounted for rotation within a rotatable tube 20, and it is driven by power mechanism, such as an electric motor 22 of suitable construction which is fixedly mounted on the stationary housing. The shaft 23 of the motor is removably connected with the spindle 18 through a telescoping joint comprising a pin 24 on the motor shaft 23 riding in a slot 25 in the hollow telescoping end 26 of the spindle 18. This permits adjustment of the wheel spindle towards and from the work.
- 20 The housing for the driving mechanism comprises a cylindrical casing 30 carrying an enlarged portion 31 secured thereto. The casing 30 has bearing members 32 and 33 (Fig. 7) mounted therein, within which the hollow shaft 20 rotates. The spindle 18 is carried on its forward end by a bearing 34 located on the inside 25 of the tapered nose 35 which has a flange 36 connected to a flange 37 on the hollow spindle sleeve 20. This construction gives a planetary motion to the grinding wheel.
- 25 The spindle 18 may be adjustably positioned in a desired eccentricity relative to the axis of the surrounding tube 20, which is widely spaced therefrom to permit the desired adjustments. This adjustment is effected by the mechanism shown in Figs. 7, 9 and 10. The nose 35 of the housing is mounted to swing about a cap screw 40 which passes freely through the flange 36 and is threaded into the flange 37 of the rotatable tube 20. At the upper end of this nose 35 and diametrically opposed to the cap screw 40 is a further cap screw 42 passing freely through an elongated arcuate slot 43 in the flange 36 and this screw is also threaded into the flange 37. Adjustment screws 44 and 45 are threaded into the flange 36, and they are arranged to contact with opposite sides of the upper cap screws 42, so that by separately adjusting these screws 44 and 45, one may swing the nose 35 about its supporting pivot 40 and thus adjust the nose and the grinding wheel spindle carried thereby 30 so that the latter will be in a desired eccentric position relative to the axis of the hollow shaft 20.
- 35 Mounted in the rear of the upper enlarged portion 31 of the housing is an internal gear 46 (Figs. 7, 11, 12 and 13) which is held in a stationary position by means of suitable pins. A small gear 47 is fixed on the end of the motor shaft 23 and thus rotates with the grinding wheel spindle 18. This gear 47 meshes with a sun gear 48 which also meshes with the internal gear 46. The sun gear 48 is carried on a pivot pin 49 fixed in the rings 50 and 51. The ring 50 is in turn threaded onto the end of the spindle sleeve 20 and forms a continuation thereof, the two parts being secured together by a set screw. The ring 51, to which the motor is pinned, has an arcuate slot 52 therein within which rides the pin 53 projecting from the inner ring 50. These parts correspond in arrangement with the slot and pin shown in Fig. 9 and permit the ring 50 and hollow shaft to swing about the axis of pin 49 and relative to the motor shaft 23 and wheel shaft 18. Two nuts 54 are threaded onto the spindle sleeve 20 and bear against the upper end of the housing 30 and thus hold the sleeve 20 in proper adjusted driving position. A cap 55 is attached as by means of a set screw to the housing so as to protect the gear mechanism from dust.
- 40 As the gear 47 is rotated by the motor shaft, 20 it drives the sun gear 48 around the internal ring gear 46 and causes the sun gear to travel in a concentric or planetary path relative to the axis of the grinding wheel spindle. The sun gear is mounted in alignment with the cap screw 40 which serves as a center about which the nose 35 swings; hence, when the grinding wheel shaft 18 is moved to vary its eccentricity by means of the adjustment members shown in Figs. 9 and 10, the gear 47 will be likewise moved 30 and will ride around the sun gear 48 and always remain in driving contact therewith. This causes the pin 49, which forms the bearing support of the sun wheel, to drive the rings 50 and 51 and the sleeve 20 and force the latter to rotate about its axis. It will now be seen that when the grinding wheel 16 is rotated on its shaft 18 by means of the motor 22, the gear mechanism in the housing will cause the hollow shaft 20 to rotate and carry the inner grinding wheel shaft 40 18 in an eccentric path around the axis of the shaft 20.
- 45 As shown particularly in Fig. 14, the grinding wheel 16 is preferably smaller in diameter than the length of the crank pin 15, and the eccentricity of the wheel axis relative to the axis of the hollow shaft 20 is so adjusted that as the wheel rotates it will move back and forth substantially the entire distance between the cheeks 57 and 58 of the crank shaft pin, so that the 50 wheel will grind the entire length of that pin. The eccentric motion of the abrasive body over the work surface causes an abrading action somewhat like the circular motion of a hand honing operation, and the rotation of the wheel prevents an uneven wear thereof and provides a break-up motion. Hence, the combined action of the two motions produces a lapped and finely finished surface. The wheel may have a flat 55 disk for its end face, but it is preferably cup shaped, since the central portion of the wheel rotates at too slow a rate to be efficient in its cutting action. Thus by making proper adjustment of the pressure of the wheel on the work and using suitable abrasive grains and wheel structure, one may obtain a very fine polishing action and not only true but polish a crankshaft and provide a desired finish.
- 60 The grinding wheels may be made of suitable material, such as crystalline alumina, silicon carbide, boron carbide or diamond grains, bonded by suitable bonds, such as the standard vitrified ceramic materials, vulcanized rubber, shellac, polymerized resins and heat hardening resinoids of the type of the phenolic-formaldehyde con- 65
- 70
- 75

densation products. Each of the wheels may be suitably shaped, either to present a sharp corner at its periphery or preferably to present a rounded corner, the radius of which corresponds with the curvature of the fillet of the crank pin. If this latter construction is adopted, then the grinding wheel may grind the entire length of the pin and to the cheek of the crank-shaft and at the same time finish the fillet and leave it in satisfactory shape and condition for use without any further grinding operations.

The grinding wheels may be held in proper contact with the crankshaft pins as the latter revolve about the axis of the crankshaft bearings by providing a connection between the work and each wheel which causes the wheel axis to travel in synchronism with the work and through a path parallel with that of the pin being ground. This is preferably effected by means of the mechanism, shown in Figs. 2 and 6, comprising two master crankshafts 60 and 62 which are rotated in synchronism with the work being ground. These shafts support and move the various wheel housings 30 as required. To this end, each housing 30 has a flange 64 (Figs. 7 and 8) projecting downwardly therefrom, which carries a dovetailed portion 65 forming a slide interfitting with an undercut dovetailed portion 66 in a support 67. The support 67 has two spaced half bearing members 68 and 69 (Fig. 2) which rest on the pins of the master cranks 60 and 62. Bearing caps 70 and 72 are suitably attached, as by cap screws, to the support 67 so as to hold the master crank pins in position.

Each master crankshaft corresponds in shape and size with the crankshaft to be polished. These masters are synchronized to rotate with each other and the crankshaft work piece by means of a common driving mechanism. This comprises a rock shaft 90 (Figs. 2 and 6) suitably mounted in bearings on the base 10 of the machine. A sleeve 91 rotatable on one end of the shaft carries a sprocket 92 which drives through a chain 93 a sprocket on the end bearing pin of the master crankshaft 60. A similar sprocket 94 on the crankshaft 60 drives a sprocket 98 on the master shaft 62 and these sprocket gears are all of the same size so that the two master shafts are revolved in synchronism. The master driving sleeve 91 is driven by means of a second sprocket thereon and a chain which in turn is driven by a sprocket 102 fixed on the head stock spindle 104, to which the crank shaft 14 is removably affixed for revolution thereby. As shown in Figs. 3 and 4, the head stock spindle 104 is mounted in ball bearings 106 and 107 within the housing 11. This spindle also carries a worm gear 108 which meshes with the driving worm 109. This worm is mounted on a shaft 110 suitably supported in bearings in the housing.

A suitable clutch mechanism may be provided for releasably connecting the worm shaft 110 with a driving pulley 112, which is driven from a suitable electric motor 114 (Fig. 2) mounted in the base of the machine, the power drive being effected by means of V-belts 115 suitably meshing with the driving pulley 112. The clutch mechanism, as shown in Fig. 3, comprises a handle 116 pivotally mounted to shift a sliding clutch member 118 keyed on the shaft 110 which connects through a suitable friction drive 120 with the shaft 121 carrying the driving pulley 112. The friction drive may comprise alternately arranged disks on the spindle 110 and rings on

the end of the shaft 121. When the clutch handle 116 is thus moved towards the right, the disks are brought into frictional driving engagement and so serve to rotate the shaft 110. A similarly arranged set of friction disks 122 at the left may serve as brake elements to stop the driven shaft when the clutch handle is thrown in the opposite direction.

A handle 130 (Fig. 1) serves to throw a yoke 132 (Fig. 4) in such a manner as to thrust a driving pin 134 into the plate 135 forming the driving element of the crankshaft 14. The pin 134 is mounted on a sliding collar 136 slidably keyed to the shaft 104. The tailstock for carrying the other end of the crankshaft comprises any suitable construction, such as a pin 200, suitably mounted in the housing. This pin 200 may be held in an outward position by a spring 201 located at the rear and within the housing so that by thrusting a crankshaft against this centering pin it will be pushed back and permit the driving plate at the other end to be suitably connected to the head stock driving spindle.

It will, therefore, be seen that the electric motor 114 drives the pulley 112, this in turn drives the shaft 110 and connected worm gear to rotate the crankshaft to be polished in synchronism with the two master crankshafts. The pins on the master crankshafts correspond in position and arrangement with those on the work, and so each of the grinding wheels is held in proper abrading contact with its associated pin. If desired, the main bearings may also be ground at the same time, and in that case the support for its grinding wheel will remain stationary and not revolve. The different grinding wheel mounts are located in different positions at any given time and thus tend to balance each other as they revolve and thus reduce any tendency for vibration within the machine.

Each grinding wheel may be suitably adjusted relative to the work. A simple device, as shown in Figs. 2, 7 and 8, comprises a clamping screw 140 operated by a suitable handle, which passes through an elongated slot 142 in the supporting member 67 and is threaded into the downwardly projecting flange 64 of the housing 30. By loosening this clamp screw, one may manually move the parts to an adjusted desired position and then set the screw again to hold the wheel as thus positioned. The wheel may be held forward against the work by means of a spring 144 (Fig. 7) which surrounds the shaft 18 and engages a shoulder 146 on the nose 35 and a pin 148 passed through the spindle 18. This spring, being under compression, tends to thrust the grinding wheel forward to a required distance which may be limited by the amount of movement permitted by the pin 148 engaging the rear of the bearing 34. This causes the grinding wheel to engage the work with a resilient pressure and thus to take up for wheel and work wear and to adjust for improper positioning of the housing on its mount 67. A micrometer mechanism may be employed to position the wheel accurately relative to the work. As shown in Fig. 7, this may comprise a screw 145 threaded into a flanged extension on the flange 64 of the housing which engages the upper end of the slide member 67 and limits the movement of the wheel mount towards the work under the influence of gravity and the spring 144.

In order to permit quick removal of the grinding wheels from the work and easy replacement of the latter, the different grinding wheel hous-

ings, which are carried on their respective mounts 67, may be simultaneously moved by a power mechanism. To that end, the master crankshafts are supported on uprights 150 and 5 152 (Fig. 2) carried on a plate 154 having downwardly projecting arms 160 fixed on and mounted to swing with the rock shaft 90. These uprights carry half bearings 156 and 157, and suitable bearing caps 158 and 159 are provided to 10 secure the main bearings of the master crankshafts to this swinging mount.

This mounting plate 154 may be moved by hand or by power, such as the fluid pressure mechanism, shown particularly in Fig. 2. To this 15 end, a rock arm 162 is fixed on the rock shaft 90 and crooked around to pivotally connect with a pitman 164 which is attached to and moved by the piston 165 mounted within the piston chamber 166 which is in turn pivotally mounted 20 at 168 on a lug projecting from the inner base of the casing 10. Fluid under pressure, such as oil, may be sent to opposite sides of the piston by means of suitable hose connections 170 and 171 connected with a manually adjustable valve 25 172 comprising three pistons 173, 174 and 175 on a piston rod 176 which is suitably controlled by a hand operated lever 177. Fluid is forced under pressure from a pump 178 through a pipe line 179 which connects only with the central 30 portion of the valve casing and beneath the valve piston 174 when the latter is in an inoperative position. The pump may be of any suitable design and connected with a pressure release valve and piping for returning the oil to an oil 35 reservoir 180 provided in the base of the machine. A return pipe line 182 connects through pipes 183 and 184 with ports located opposite pistons 173 and 175 in the valve casing. Hence, when the valve rod is moved to the left, oil is 40 sent through the pipe line 170 to move the piston 165 towards the left and the pipe 171 becomes an exhaust pipe connecting the valve chamber with exit pipe 184. When the valve is moved to the right, the mechanism is similarly arranged 45 to drive the piston to the right. When the piston is moved to the left the plate 154 carrying the wheel housings is elevated to throw the wheels back towards the right and out of contact with the work, so that the work may be 50 moved and a new crank shaft and new wheels put into position.

It will be understood that one may employ suitable mechanisms well known in the industry for mounting the various parts and driving the 55 same so as to take care of the different shapes, types and sizes of crankshafts and numerous modifications may be made in the mechanism as required. Also, one may make a simplified machine for grinding a single pin by employing only 60 one of the wheel mounts and associated parts. Various other features above described may be omitted, and numerous changes may be made by substituting equivalent constructions for those herein described. Hence, the above description of a machine embodying all of the inventive features is to be interpreted as being 65 illustrative of the principles of the invention and not as limitations thereon except as required by the scope of the claims appended hereto.

70 I claim:

1. A crankshaft grinding machine comprising means for supporting a crankshaft for rotation about the axis of its bearings, a grinding wheel, means for rotating the wheel, means for revolving it eccentrically relative to its axis of rota-

tion, and means for supporting the flat side of the wheel in abrading contact with the crank pin as the latter revolves about the crankshaft axis.

2. A crankshaft grinding machine comprising 5 means for supporting a crankshaft for rotation about the axis of its bearings, a grinding wheel having its flat face of smaller diameter than the length of the pin and in abrading contact with an eccentrically mounted crank pin, means for 10 rotating the wheel, means for revolving it eccentrically relative to its axis of rotation as it grinds the pin, and means for holding the wheel in abrading contact with the pin during revolution thereof about the crankshaft axis. 15

3. A crankshaft grinding machine comprising means for supporting a crankshaft for rotation about the axis of its bearings, a grinding wheel having its end flat face of shorter diameter than the length of the crank pin and in abrading 20 contact with the same, means for rotating the wheel and for revolving it eccentrically as it grinds the pin, and means including a master crankshaft for holding the wheel in contact with the work and revolving it in synchronism therewith. 25

4. A crankshaft grinding machine comprising means for supporting a crankshaft for rotation about the axis of its bearings, a grinding wheel having its flat face in abrading contact with an 30 eccentrically revolvable crank pin, a motor connected to rotate the wheel and means driven by said motor for revolving the wheel eccentrically as it grinds the crankshaft.

5. A crankshaft grinding machine comprising 35 means for supporting a crankshaft for rotation about the axis of its bearings, a grinding wheel having its flat end face in abrading contact with an eccentrically revolvable crank pin, a support for said wheel, an electric motor on said support 40 connected to rotate the wheel, means driven by said motor for revolving the wheel axis eccentrically and means for holding the wheel in contact with the pin during revolution of the latter.

6. A crankshaft grinding machine comprising 45 means for supporting a crankshaft for rotation about the axis of its bearings, a master crankshaft axially parallel with the work, means for revolving the two crankshafts in synchronism, a grinding wheel mounted to grind on its flat end 50 face, means whereby the master crankshaft holds the wheel in abrading contact with a crank pin during eccentric revolution thereof, means for rotating the wheel to grind the pin, and means for revolving the wheel axis eccentrically 55 during grinding.

7. A crankshaft grinding machine comprising 60 means for supporting and rotating a crankshaft about the axis of its bearings, a plurality of grinding wheels, means for holding the wheels with their end plane faces in abrading contact with the crank pins during eccentric revolution thereof, means for rotating the wheels, means for revolving the wheels eccentrically relative to 65 their axes during grinding and mechanism for moving the wheel simultaneously towards and from the work.

8. A crankshaft grinding machine according 70 to claim 1 which comprises means for adjusting the grinding wheel towards and from the work.

9. A crankshaft grinding machine according to claim 1 comprising means for varying the eccentricity of revolution of the grinding wheel axis.

10. A crankshaft grinding machine according 75

to claim 3 comprising a rotatable grinding wheel shaft, a hollow shaft eccentrically surrounding said shaft and supporting the same and a motor directly connected to the wheel shaft and indirectly connected to rotate the hollow shaft.

5 11. A crankshaft grinding machine according to claim 7 which comprises a common movable support for all of the grinding wheels and fluid pressure mechanism for moving said support.

10 12. A crankshaft grinding machine comprising means for supporting and rotating a crank-

shaft, a set of supporting shafts and grinding wheels thereon having their flat faces arranged to grind the crank pins, a motor for each wheel, means for connecting each grinding wheel shaft directly to the motor shaft, a rotatable hollow shaft eccentrically supporting each wheel shaft, means connected to each motor for rotating the hollow shaft and revolving the wheel shaft and means to hold each wheel in contact with its associated revolving crank pin.

10

HERBERT S. INDGE.
